US00D899301S

(12) **United States Design Patent** (10) Patent No.: **US D899,301 S**
Samokhvalov et al. (45) Date of Patent: **** Oct. 20, 2020**

(54) **ALL-TERRAIN VEHICLE**

(71) Applicant: **Ensenor Enterprises Limited**, Nicosia (CY)

(72) Inventors: **Sergei Samokhvalov**, Kozyn (UA); **Volodymyr Shkolnik**, Kyiv (UA)

(**) Term: **15 Years**

(21) Appl. No.: **35/507,334**

(22) Filed: **Feb. 27, 2019**

(80) **Hague Agreement Data**

Int. Filing Date: **Feb. 27, 2019**

Int. Reg. No.: **DM/202425**

Int. Reg. Date: **Feb. 27, 2019**

Int. Reg. Pub. Date: **Aug. 30, 2019**

(30) **Foreign Application Priority Data**

Sep. 4, 2018 (UA) S201802229

(51) **LOC (12) Cl.** **12-13**

(52) **U.S. Cl.**

USPC **D12/12**

(58) **Field of Classification Search**

USPC D12/12, 1, 92

See application file for complete search history.
